UNITED STATES PATENT OFFICE.

ALEXANDER N. SCHANSCHIEFF, OF NEW YORK, N. Y., ASSIGNOR TO FERDINAND STRAUSS, OF YONKERS, NEW YORK.

TOY GUN.

1,287,769.

Specification of Letters Patent. Patented Dec. 17, 1918.

Application filed July 23, 1918. Serial No. 246,323.

To all whom it may concern:

Be it known that I, ALEXANDER N. SCHANSCHIEFF, a citizen of the United States of America, residing at New York city, county 5 and State of New York, have invented certain new and useful Improvements in Toy Guns, of which the following is a full, clear, and exact description.

This invention relates to improvements in 10 toys, the objects being to provide a toy to simulate an armored automobile, including a miniature gun, special means being provided to cause powder to belch from the gun to simulate puffs of smoke, and also to produce a sound, to simulate a report, simultaneously with the puffs of the smoke.

The special object of this invention is to provide an inexpensive device of this character, which is durable enough to withstand 20 ordinary usage and which, by simple mechanism, accomplishes the objects above described. Further details of improvement and advantages flowing therefrom, will hereinafter appear.

25 In the drawing which accompanies this specification;

Figure 1 is a longitudinal sectional view of an embodiment of my improvement;

Fig. 2 is a bottom plan view thereof; and 30 Fig. 3 is a top plan view of the device.

As herein embodied, the device consists of a suitable box-like structure 4 upon which is pivotally mounted a turret 5 provided with a miniature gun 6. The turret 5 is 35 in the form of an inverted cup having a removable cover 7 to the inside of which is secured a bellows 8 adapted to receive powder, such as talcum or powdered chalk, through an opening 9 normally closed by a 40 cork or stopper 10. The bellows 8 is connected to the gun 6 by a flexible hose 11. The turret 5 is pivotally secured to the top 12 of the box or support 4 by a tubular bushing 13 having a flange 14 which overlaps the bottom 15 of the turret 5. The bushing 14 will be suitably fastened to the support 4.

To produce puffs of smoke, the bellows 8 will be operated to alternately slightly 50 collapse and expand, which action will cause the powder therein to issue from the nozzle of the gun, a little at a time in the form of puffs. To operate the bellows, I employ a spring-motor 16. The motor 16 operates a shaft 17 having a crank-arm 17^a to engage

yieldable resilent arms 18 and 19. The arm 19 carries an upstanding post 20 which passes through bushing 14 and contacts with the bellows 8. One end of arm 18 is secured to the frame 21 at 22. The frame 21 supports the motor 16. It will be seen in Fig. 2 that the frame 21 carries the motor and arms 18 and 19 and is inserted into the box-like support 4 and is secured thereto by ears 23 and nails or screws 24. By this means I am able to assemble the motor and arms 18 and 19, after which the frame can be inserted into place. The rotation of shaft 17 will cause the crank-arm 17^a to force the arm 18 downwardly during each 70 revolution of the shaft 17. As soon as the crank-arm clears the projection 25 on the arm 18, it will snap upwardly and cause the post 20 to snap against the bellows 8. The snap action of the post will cause powder 75 to be forced from the gun in the form of short puffs, instead of a drawn out line of smoke.

Adjacent the arm 18, I place the arm 19 having an extension 26 similar to the extension 25 of arm 18. The arm 19 is further provided with a raised portion or teat 27 to contact with wall 12 of the support 4. The action imparted to arm 19 will be the same as the action imparted to arm 18. The 80 snapping action of the arm 19 will cause a sound, to simulate reports, simultaneously with the production of the puffs of smoke. The arm 19 is operated by the crank 17^a which contacts with projection 26 on said 90 arm 19. The gun 6 and bellows 8 are connected for separation by means of the flexible tube 11. The device, while simple, is arranged for ready disassemblage in case repair is needed. 95

The gun 5 can be moved in a circle by moving the turret upon its pivot 13:

The support is provided with rear wheels 27 and a front steerable wheel 28.

The motor 16 consists of a spindle 29 surrounded by a spring 30. One end of said spring is connected to a ratchet 31, having in engagement therewith a pawl 32, said ratchet being carried by the spindle 29. The other end of the spring is connected to a 100 gear 33 meshing with a pinion 34 on shaft 35. Shaft 35 also carries, adjacent the opposite end, a gear 36 meshing with a pinion 37 on crank-shaft 17. Shafts 35 and 17 carry balance wheels 38 and 39 and 40, re- 110

spectively, in the form of intermeshing gears. The spindle 29 is rotated to wind up the spring 30 by means of a handle 41.

To maintain the arms 18 and 19 in proper position to hold the extensions 25 and 26 in the path of rotation of the crank-arm 17^a, I provide a bracket 42 on the frame 21. The bracket 42 is provided with an opening 43 through which the end members 44 and 45 of the arms 18 and 19 pass.

What I claim as my invention is:

1. In a toy, a support, a gun mounted thereon, a bellows connected therewith to retain powder, a motor mechanism, a yieldable resilient arm operated by the motor, and means associated with the arm to contact with said bellows to operate same to force powder therefrom.
2. In a toy, a support, a gun mounted thereon, a bellows connected therewith to retain powder, a motor mechanism, a shaft operated by the motor, a yieldable resilient arm, a projection carried thereby, means carried by the shaft to contact with said projection and depress said arm during the rotation of said shaft, and a post carried by the arm to contact with said bellows to operate same to force powder therefrom.
3. The combination of a toy-gun, a bellows associated therewith to retain powder, a flexible hose connecting the bellows and gun, and means to operate the bellows.
4. In a toy, a support, a gun carried thereby, a bellows arranged to retain powder connected therewith, a yieldable resilient arm, a post carried thereby, and integral therewith arranged to contact with said bellows, a crank, means to operate the crank, and means carried by the arm positioned to be engaged by said crank.
5. The combination of a toy-gun, a bellows connected therewith, and arranged to contain powder, and means to be snapped against said bellows to force powder therefrom into and through said gun.
6. The combination of a support, a gun carried thereby, a bellows to contain powder

connected therewith, a resilient arm arranged to be snapped against the bellows to force powder therefrom into and through 50 said gun, a resilient arm arranged to be snapped against the support to simulate a report, and means to simultaneously actuate said arms.

7. The combination of a support, a gun 55 carried thereby, a bellows to contain powder connected therewith, a resilient arm, a post carried by the arm and integral therewith to contact with said bellows, said arm and post being formed out of a single strip of resilient 60 wire connected at one end with said support, a second arm adjacent the arm first named, consisting of a single strip of resilient wire connected at one end to said support, said second arm having a teat intermediate its 65 ends to contact with said support, a projection carried by each arm at its free end, a crank to releasably engage said projections to operate said arms, and means to actuate the crank.

8. The combination of a support, a gun carried thereby, a bellows to contain powder connected therewith, a resilient arm, a post carried by the arm and integral therewith to contact with said bellows, said arm and post being formed out of a single strip of resilient wire connected at one end with said support, a second arm adjacent the arm first named, consisting of a single strip of resilient wire connected at one end to said support, said second arm having a teat intermediate its 70 ends to contact with said support, a projection carried by each arm at its free end, a crank to releasably engage said projections to operate said arms, means to 75 actuate the crank, and a guide for the free ends of the arms to maintain the projections in the path of rotation of said crank.

Signed at New York city, N. Y., this 8 day of July, 1918.

ALEXANDER N. SCHANSCHIEFF.
